UNITED STATES PATENT OFFICE.

GILBRETH DAWSON, OF ROCKVILLE, CONNECTICUT.

MECHANISM FOR RECIPROCATING THE TUMBLERS OF CARDING-MACHINES.

SPECIFICATION forming part of Letters Patent No. 361,492, dated April 19, 1887.

Application filed November 15, 1886. Serial No. 218,970. (No model.)

To all whom it may concern:

Be it known that I, GILBRETH DAWSON, of Rockville, in the county of Tolland and State of Connecticut, have invented an Improved Mechanism for Reciprocating the Tumblers of Carding-Machines, of which the following is a specification.

My invention consists, substantially, in the combination of the feed-roll and tumbler of a carding-machine with a driving-worm on the shaft of the feed-roll, a worm-wheel and attached eccentric, a right-angular lever one end of which engages with the eccentric and the other with a grooved collar on the shaft of the tumbler, and a standard which supports the worm-wheel and lever.

The object of this invention is to provide means for imparting a slow endwise-reciprocating movement to the tumbler, in order to prevent the wire on the tumbler from wearing in grooves and the necessity of frequent grinding to keep a uniform surface on the clothing of the tumbler, and thereby securing more perfect work and economy of card-clothing and labor.

All previous attempts within my knowledge to reciprocate tumblers have been without the combination of worm, gear, and lever, and have proved futile, for the reason that the motions have been too rapid, carrying the stock sideways, which is decidedly objectionable.

In the drawings, Figure 1 shows a side elevation of the improved mechanism with the two shafts in section; Fig. 2, a posterior view of the worm-wheel and eccentric attached; Fig. 3, a front view of the perpendicular portion of the right-angular lever; Fig. 4, a plan of the parts shown in Fig. 1.

Corresponding letters refer to corresponding parts in the several views.

S indicates the standard, with flanges F at each end projecting about two inches; B B, holes for inserting bolts to secure the standard on the inside of the carding-machine frame; D, a stud screwed into the upper flange, F, upon which the worm-wheel W, with eccentric

E attached, revolves; P, the perpendicular portion of the right-angular lever, having lugs L L, between which eccentric E revolves; O, an oblong slot in lever P, through which stud D passes, giving space for vibration of the lever P; V, a screw forming a fulcrum at the bottom of lever P; H, the horizontal portion of the right-angular lever, engaging by means of dog G with a grooved collar, C, on tumbler-shaft T; M, a driving-worm secured on the end of feed-roll R and gearing into worm-wheel W, and when the carding-machine is in operation communicating a slow endwise-reciprocating motion to the tumbler T.

I am aware that it has been proposed to impart a slow endwise-reciprocating motion to a stripper operating upon the surface of a ring or other doffer by means of a worm upon the shaft of the doffer, a worm-wheel engaging said worm, and having a crank-pin which engages the slotted end of a vibrating lever, the other end of which lever is forked to engage a grooved collar on the stripper-shaft. Such construction of vibrating devices, and such combination therewith of doffer and stripper, I do not claim; but what I do desire to cover is the specific construction and combination set forth in the following claim.

Having thus described my invention, what I claim as new, and desire to secure by Letters Patent, is—

In a carding-machine, the combination of the feed-roll provided with the driving-worm M, the tumbler having the shaft provided with the grooved collar C, standard S, provided with flanges F F, stud D, and fulcrum V, the right-angular lever H P, provided with lugs L L and dog G, and worm-wheel W, with attached eccentric E, all constructed, secured, and operated in the manner and for the purposes herein specified.

Rockville, Connecticut, November 12, 1886.

GILBRETH DAWSON.
